UNITED STATES PATENT OFFICE.

LÉON DUFOUR, OF GENEVA, SWITZERLAND.

COMBUSTION TURBINE.

Application filed May 24, 1922. Serial No. 563,200.

To all whom it may concern:

Be it known that I, LÉON DUFOUR, a citizen of Switzerland, residing at Geneva, Canton of Geneva, in the Confederation of Switzerland, have invented certain new and useful Improvements in Combustion Turbines, of which the following is a specification.

Under the general term combustion turbine there is herein to be understood any machine which generates motive force in which the expansion of gases produced by the combustion of any fuel such as gas, oil, tar, petroleum, petrol, coal and explosives, etc., is utilized by a turbine. It is known that combustion turbines called also gas turbines may be divided into two main classes, i. e., turbines at constant pressure and explosion turbines. This invention applies to both of these classes of combustion turbines.

The invention herein claimed relates to an apparatus in which the cooling of the wheels and of the blades of the wheels of a combustion turbine allows a turbine to be constructed which possesses excellent conditions of efficiency and an arrangement for carrying out such process in a combustion turbine.

The apparatus consists, in a combustion turbine, in which the wheels and especially their blades are cooled by passing cold air and if desired the cold gases necessary for combustion and for operating the turbine into such wheels and blades, and also if desired the burnt gases after they have performed their work in the turbine and after they have been suitably cooled, while utilizing the passage of the air and it may be gases in the wheels of the turbine at the same time to increase the pressure of such air and gases.

The apparatus also consists of a turbine having a plurality of pressure stages, and one or more speed stages per pressure stage, the turbine having a plurality of wheels in which wheels and their blades are so constructed as to serve both as turbine wheels and compressor wheels, and in which the wheels and their blades successively receive burning active gases coming from the combustion or explosion chamber or chambers, gases whose speed and pressure is utilized by the wheels and the cold air or gases compressed by such wheels. In such turbines the blades of the same wheel are therefore successively employed to transform the pressure and speed or speed only

of the active hot gases into rotary movement of the wheel, then to transform the rotary movement of the wheel into speed and into pressure of the air or cold gases to be compressed. The heat communicated to the blades and to the wheel by the hot active gases will be transmitted as produced by the wheel and the blades to the air or to the cold gases so that the wheel and the blades will be maintained at a temperature intermediate between the temperature of the hot active gases and that of the air or cold gases.

Finally such arrangement comprises several parts or machine elements which will herein be successively described and whose application to the new arrangement for a new object also constitutes novelty.

The invention is illustrated by way of example in the accompanying drawings of which—

Fig. 1 is a diagrammatic longitudinal section of a combustion turbine for carrying out the process.

Fig. 2 is a transverse section taken on the line 2—2 of Fig. 1.

Figs. 3 and 4 show two arrangements of a wheel for such turbine.

Figs. 5, 6, 7, 8, 9, 10 and 11 show details of the construction of the blades of such wheel and the method of securing them.

Finally Figs. 12, 13 and 14 show three views of a wheel provided with different arrangements of blades.

The turbine illustrated by way of example in Figs. 1 and 2 is a combustion turbine burning liquid fuel, crude oil for example, of the axial type having five pressure stages, each pressure stage having one speed stage only, three of such stages working above atmospheric pressure and the other two stages working below atmospheric pressure. The turbine is divided into two sections of which the upper section as illustrated comprises nearly three quarters of the circumference where the wheels work as rotary compressor wheels, and the lower section where the wheels work as turbine wheels properly so called.

In Fig. 1, *a* is the turbine shaft, *b*, *b*¹, *b*², *b*³, *b*⁴ and *b*⁵ are the five turbine wheels keyed on shaft *a*. Each wheel consists of the portion *b* which comprises the hub keyed upon the shaft and flange *c* connected to portion *b* by ribs *d* forming portions of the blades. A circular channel *e*, *e'* is thus

formed in each wheel between portions *b* and *c*. The blades *f* are fixed at the circumference of each wheel between portion *b* and flange *c*. The blades are, outwardly 5 to the wheel, of the general shape of the blades of steam turbines, but they are open both at their inner radial end and at their outer radial end. The blades penetrate radially more or less into the interior of each 10 wheel. They are for this object and for each wheel formed of two or more different lengths as indicated by the dotted lines *f'*. In the upper portion of Fig. 1 where the 15 turbine works as a compressor, *g*, *g*², ..., *g*⁵ are diffusing channels, i. e., circular spaces provided with blades fixed at their external radial portion. Blades *f* of the wheel pass with very little play into the internal radial portion of these channels. The diffusing 20 channels communicate with other channels *h*¹, *h*² ..., *h*⁵ which connect channels *g*¹, *g*³ and *g*⁴ with the inlet of the wheel following, and channels *g*² and *g*⁵ with the channels *h*² and *h*⁵ leading to the outlet pipe for 25 the gases or air. *i*¹ is the inlet tube for the burnt gases into the compressor and *i*² the outlet tube for the same burnt gases into the atmosphere. *i*³ is the inlet tube for the air required for combustion and *i*⁴ the outlet tube for such air after its passage into 30 the compressor section.

In the lower portion of Fig. 1 in which the turbine acts as a turbine properly so called, *k* *k* are channels leading gases passing 35 out of the blades of one wheel to the guide blades of the following stage, *m* *m* are the guide blades of each stage. *n* is the inlet tube for hot gases passing into the turbine and passing out of the combustion 40 or explosion chamber, which is not shown in the drawing. *o* is an outlet tube for said gases passing out of the turbine after having traversed the blades of the five wheels. *p* *p* are diaphragms separating the different pressure stages of the turbine from each 45 other. *p*¹ *p*¹ are portions of said diaphragms which being situated very near to the inlet into channels *e* of wheels *b*, serve to close the inlet to such channels when they 50 pass into the section of the turbine properly so called. Behind each closing portion *p*¹ is a channel *u* which allows the internal radial portion *q* of the channel or channels immediately preceding the turbine section 55 to communicate with the internal radial portion of the channel or channels immediately following the turbine section.

Lastly *s* *s* is the outer wall or casing of the machine.

Fig. 2 is a transverse section of the same turbine taken on the line 2—2 of Fig. 1, said line deviating from the straight according as the section relates to the compressor portion or to the turbine properly so called. In Fig. 2, *a* is the turbine shaft, *h* *h* chan-

nels which leads air into the inner part of the compressor, and *g* the circular space forming a continuation of the preceding diffuser and which allows such diffuser to communicate with channels *h*. *i*³ is the inlet tube for air into the compressor section. In the lower or turbine section *p* is the diaphragm separating one pressure stage from the other pressure stage of the turbine. *p*¹ is the portion of such diaphragm which 70 closes the inlet of the channels of the wheel. *k* is the channel leading the gases passing out of the blades of the preceding wheel to the directing blades *m*. *r* *r* are walls separating the turbine section from the compressor section, *r*¹ is an enlargement of wall *r* placed at the spot where the wheel passes from the compressor section to the turbine section and serving as the wall *p*¹ to close the inlet of the channels of the wheel, such channels being marked *e* in Fig. 1. As seen in the figure such closing surface *r*¹ *p*¹ is set at an angle with respect to the turbine section and behind said portion *r*¹ *p*¹ is channel *u* shown dotted, but which can well be seen in Fig. 1; this channel allows the internal radial portion of channels *h* preceding the turbine section to communicate with the end portion *u*¹ of channel *u* as shown in Fig. 2. *s* *s* is the outer wall or casing of the machine.

In Fig. 3 which shows one method of constructing a wheel *b* is the wheel hub forged in a single piece with the main disk *b*. *d* *d* are ribs forged together with the disk and hub or formed by cutting away metal. Ribs *d* are sharpened at *d*¹ and at *d*² so that when once the wheel is mounted such ribs form blade elements. *c* is a flange or secondary disk of which the enlarged portion *c*¹ is in mounting fixed upon the corresponding rounded portion of ribs *d*. In Fig. 3 flange *c* is shown separate from main disk *b*, and therefore before being mounted upon the disk. The lesser diameter *t*¹ of enlarged portion *c*¹ is a little smaller than diameter *t* above the commencement of the ribs so that the flange *c* should be mounted while hot when the temperature of the flange is sufficiently high for diameter *t*¹ to be a little larger than diameter *t* of the ribs. After cooling flange *c* is then firmly applied on ribs *d* and flange *c* will be in some measure in one with main disk *b*. The disk and flange maintained at the required distance by ribs *d* will form between them a circular channel having walls converging towards the outer circumference provided the flange seen in section is inclined. *w* *w* and *v*¹ *w*¹ are circular dovetail grooves formed on the internal faces of disk *b* and of flange *c*, said grooves serving to fix the blades. In Fig. 4 which shows another method of making the wheel the same letters designate the same parts as in Fig. 3. In this other 130

arrangement enlarged portion c^1 of the flange is provided at x with an internal screw thread and screws on to ribs d which are at y provided with an external screw thread. 5 These two ways of mounting the flange upon the disk may also be combined together in this sense that the flange may be screwed while hot upon the ribs on the disk.

Fig. 5 is a front elevation of one of the 10 blades fixed on the wheel between the main disk and the flange. f shows such blade which is formed of a sheet of metal suitably curved or forged to the shape of a gutter just as in a normal steam turbine blade. The 15 blade however in this case remains open at the internal radial end as also at the external radial end because it must serve both as turbine blade and as compressor blade. Lugs $z z$ formed in one with the blade serve to secure it by engaging grooves $w w^1$ in disk b and flange c . Such lugs may be dovetail as are the grooves indicated in the figure but this is not a necessity. The figure shows 20 two lugs and two grooves, one on each side, but the number of lugs on each blade and their corresponding grooves may be greater.

Fig. 6 is a profile view of the same blade, taken on the line 6—6 of Fig. 5.

Fig. 7 is a plan of the same blade and 30 neighbouring blades taken on the line 7—7 of Fig. 5. In Fig. 7, $z^1 z^1$ are distance plates also seen in section which are interposed between each blade and which are maintained in grooves $w w^1$. It is mainly to fix these 35 plates that grooves $w w^1$ are made dovetail and of course plates z^1 are provided with corresponding dovetails. The plates are inserted into the groove by means of a notch indicated by dotted lines q in Fig. 5, such 40 notch being then filled up in any suitable manner. If the blades in place of being radial as indicated in Fig. 5 are inclined with respect to the radius of the wheel as shown in Figs. 13 and 14 the distance plates 45 which are inclined also may in certain cases be inserted into the groove in a very simple manner; to insert them it is only necessary to incline them still more and then to straighten them. The last plate of a tier is 50 inserted after it has been curved sufficiently to allow it to enter the groove, it is then flattened when in position. These plates maintain the distance between the blades and cooperate in maintaining the blades 55 rigidly fixed.

Fig. 8 shows in front elevation, side elevation and plan two different types of such plates. The left hand plate is intended to 60 separate radial blades such as those indicated in Fig. 12 and that on the right hand to separate inclined blades such as those indicated in Figs. 13 and 14.

Fig. 9 shows a blade similar to that shown 65 in Fig. 5; in Fig. 9 however the inclination of flange c seen in section continues as far

as the outer circumference of said flange so that the circular channel formed between flange c and main disk b is converging up to its end and so that the portion of the blade engaging such channel is trapezoidal as is 70 clearly shown in Fig. 9. In Fig. 5 the inclination of flange c ceases at the base of blade f so that the walls of the channel between the flange and the main disk become parallel near to the blade and so the portion of the 75 blade engaging in such channel is rectangular. In Fig. 1 the different wheels are constructed according to both these methods.

Fig. 10 shows one of the long blades, f^1 with its two sets of lugs $z z$ and $z^2 z^2$ which 80 are lodged in grooves $w w^1$ and $v v^1$ on the wheel. Each wheel comprises a certain number of short blades and a certain number of long blades which may of course be provided with more than two pairs of lugs. A same 85 wheel may thus be provided with blades of three or more different lengths.

Fig. 11 shows a blade to a larger scale seen in end elevation and outside the wheel. It will be seen from this figure that the portion of the blade which extends beyond the wheel is pointed at m' and n' just as in a 90 normal steam turbine blade. For reasons which will be explained later angles β^1 and β^2 for the inlet to, and it may be the outlet 95 from the blade, are relatively very large measuring more than 40° .

Fig. 12 shows a wheel with its blades in 100 position seen in front elevation. In this arrangement the blades are mounted radially and there is always one long blade f' for two short blades f . The circular grooves $w v$ which serve to maintain the blades in position are indicated by dotted lines.

Fig. 13 shows another arrangement of 105 wheel in which the blades are no longer mounted radially but are inclined rearwardly with respect to the direction of rotation of the wheel, and such inclination can easily be obtained by interposing between the 110 blades in the grooves $w v$ distance plates having an inclined shape such as indicated on the right hand side of Fig. 8. In this figure the wheel shown always has one long blade f^1 for every three short blades f .

Finally Fig. 14 shows a third arrangement of wheel also having inclined blades but having for each long blade f^1 four short blades f and one medium size blade f^2 intermediate between and interposed symmetrically between the short blades.

In this arrangement there is formed in the disk and in the flange a third pair of circular grooves w^2 intermediate in size between grooves w and v ; such grooves are particularly useful for fixing the base of medium size blades f^2 while they also support the middle portion of long blades f^1 . The number of types of blades of different lengths may of course be increased and they 130

may be arranged in no matter what order with a view to obtaining a compressor wheel of advantageous shape.

The working of the turbine shown diagrammatically and by way of illustration in Figs. 1 and 2 can easily be understood; the air necessary for combustion is sucked from the atmosphere through tube i^3 and is compressed to the required pressure by the three wheels b^3, b^2, b^1 shown on the left hand side of Fig. 1. These wheels at the upper section of the machine behave exactly as the wheels of an ordinary rotary compressor. Air is first compressed inside each wheel by reason of the difference between the relative speeds of inlet and outlet and by centrifugal force. The absolute outlet speed of air from the wheel is then transformed into pressure by fixed blades g of the diffuser and it may be also by the blades or wall of channels h leading back air to the inlet of the wheel following. After combustion or explosion of the combustible mixture in the chamber or chambers, the active hot gases are led through tube n to the first series of guide blades m which direct such gases upon the blades of first wheel b^1 in the lower section of the machine which is the turbine section. The said first wheel from the turbine point of view is at the same time the last wheel from the compressor point of view. In passing out from the blades f of this wheel the gases are directed by channel k into guide blades m of the second stage of the turbine and so on until the last stage and to last wheel b^5 . In each series of guide blades the gases expand to a lower pressure and therefore increase in speed which is then utilized by the corresponding wheel. In passing out of last wheel b^5 the gases have fallen to a pressure lower than atmospheric pressure and they must be compressed in order that they can escape into the atmosphere. At the moment when the blades of a wheel are passing from the compressor section to the turbine section, the air or burnt gases must cease to circulate radially between such blades in order to prevent the air or gases entering into the turbine section and, to allow the hot active gases which pass through the turbine to pass axially into the blades. With this object closing portions $p^1 r^1$ of the diaphragms or walls p and r are provided as is clearly shown in Fig. 2. At a little distance in front of such portions $p^1 r^1$ is the inlet into channels e of the wheels and $p^1 r^1$ have for their object the closing of such inlet channels and thus preventing air or gases entering into channels e of the wheels when the blades of such wheels are passing through the turbine section. It is even preferable that the closing of the channels e should commence a moment before the corresponding blades pass

from the compressor section into the turbine section in order that the air or the gases in the channels e at the moment of closing still have time to pass through the wheel as far as the blades and can still escape into the compressor section. In the same manner it is preferable that closing of the inlet of channels e should cease before the blades have left the turbine section so that the air or the gases may have time again to enter the wheel and to traverse it radially and to pass radially between the blades when these reenter the compressor section. This is the reason why closing portions $p^1 r^1$ in Fig. 2 is set at an angle in advance of the direction of rotation of this wheel with respect to the turbine section. In rear of the closing surface a channel u places the internal radial portion of the channel h immediately preceding the turbine section into communication with the internal radial portion of the channel h immediately following such turbine section so that continuous circulation of the air or gases in the compressor may not be interrupted except for the interruption necessary in the interior of the wheel as has above been explained.

The method of constructing the wheels and blades and the method of fixing the blades in the wheels will easily be understood from the description of Figs. 3 to 11. In order to improve the working of the compressor the blades may be inclined rearwards with respect to the direction of movement of the wheel as has been indicated in Figs. 13 and 14. In this case the guide blades of the turbine may be given an inclination suitable to this inclination of the blades of the motive wheels. In each wheel blades of different lengths may be alternated as is indicated in Fig. 12 to 14, in brief, inside such wheels the blades may have the shape and be arranged as is most suitable from the compressor point of view.

The advantages of the process and the method of carrying it out are evident by mere inspection of Figs. 1 and 2. The cold gases or air passing into the compressor commence at once to cool the blades which in the turbine section are in contact with the burning gases. The blades and the wheels will thus at each stage of the machine have a temperature intermediate between that of the burning gases and that of the cold air or gases. Knowing the value of the coefficient of transference of heat between the gases or the air and the blades for different speeds, pressures, and temperatures of the gases or air and for the different temperatures of the blades, the necessary speeds and cross sections may easily be found for the burning gases on the one hand and for the cold gases or air on the other hand in order so to arrange that the blades do not exceed a limited predetermined

temperature. It may be noted that cooling is facilitated by the fact that the cold gases or air pass radially between blades which have a relatively large radial height while the burning gases traverse blades axially and a portion only of their radial height. The heat transmitted by the burning gases to the blades may partially be distributed over their whole radial height and will thus more easily be dissipated by the cold gases and air. For example, in the first wheel of the turbine the gases may be allowed to enter at a temperature of 900° or 1000° C. or more and the arrangement however be such that the blades do not exceed a maximum temperature of 400° C.

From then on turbines having a plurality of pressure stages may as shown by the above described example, be employed as combustion turbines, for example, turbines having 5 to 10 pressure stages or more, that is to say the turbines will possess efficiencies much greater than turbines having a single pressure stage as has heretofore been proposed for combustion turbines.

It will be of advantage in each wheel that the pressure in the compressor section should approximately be the same as the pressure in the turbine section as the passage of air or gases from one section to the other, where the wheel passes from one to the other, would thus be avoided and so loss of air or gases. It is known however in rotary compressors that when the tangential speed of the wheels does not exceed 150 to 200 metres per second that the increase of pressure obtained from each stage of wheel and diffuser is relatively small and is less than the fall of pressure which can be utilized in a corresponding combustion turbine stage with the same tangential speed of the wheel.

A method of obviating the difficulty of obtaining substantially the same pressure in a compressor section stage as in the corresponding stage of the turbine section will be to lessen that portion of the speed of the burning gases utilized by each turbine wheel in the turbine section by increasing above the usual limits the angle of inclination of the guide blades upon the plane of the wheel. In normal steam turbines this angle varies between 15 and 20°. An angle of at least 30° may here be taken. The inlet angle of the wheel blades will then have a value of at least 40°, a value much greater than the usual value. The proportion of the speed of the gases then utilized by the wheel and transformed by it into work will be less great than if the angles were normally small while the absolute speed of outlet of the gases from the blades will be greater; such absolute outlet speed is moreover utilized to a large extent by the crown of guide blades at the stage following. This means that the fall of pressure utilized by one stage of the

turbine section will be smaller than in a turbine having normal angles for the guide blades and the blades of the wheel and thus it will be easier to make this small fall of pressure correspond to the increase in the pressure of the air or of the gases in the corresponding stage of the compressor section.

Moreover the use of such large inlet angles and it may be outlet angles of the blades have two other advantages: the loss by friction of the relative speed of the active gases in a less curved blade will be smaller and consequently the real efficiency of the turbine will be improved, and as the back of the blade will be less curved the blade will be better suited to act as compressor blade for it is to be noted that in the compressor section it is the convex surface or the back of the blades which is the surface directly acting upon the air or gases to be compressed.

The apparatus herein shown and described is illustrative of one manner in which my invention may be carried out, and it is to be understood that the same may be varied within the scope of the claims without departing from the nature and spirit of the invention.

Having now particularly described and ascertained the nature of my invention and in what manner the same is to be performed, I declare that what I claim is:

1. In an apparatus of the class described, a casing, a plurality of rotors each having a passage therethrough, a plurality of blades carried by the said rotors, means for admitting air into the casing and to the said passages in the rotors during a part of each revolution thereof, for utilizing said blades as compressor blades, means for closing the entrance to the passage in each rotor during the remainder of each revolution thereof, means for directing combustion gases to the said blades during the said remainder of each revolution thereof, and thereby utilizing the said blades as turbine blades during this portion of the revolution, and inlet and outlet connections for the said combustion gases.

2. In an apparatus of the class described, a casing, a plurality of rotors mounted in the casing, and each having a passage therethrough, a plurality of blades mounted in, and extending from the said rotors, means for admitting air into the casing and to the said passages in the rotors during part of each revolution thereof, to then utilize the said blades as compressor blades, partition walls in the casing for closing the entrance to said passages in the rotors during the remainder of each revolution thereof, means for directing combustion gases to the said blades during the said remainder of each revolution thereof, for then utilizing the

said blades as turbine blades, and inlet and outlet connections for the said combustion gases.

3. In an apparatus of the class described, 5 a casing, a plurality of rotors mounted in the casing, webs in the rotors providing in each thereof a plurality of passages, a plurality of blades mounted in each rotor, means for admitting air into the casing, and to 10 the entrance to the said passages in the rotors during a part of each revolution thereof, for then utilizing the blades as compressor blades, means for closing the entrance to the passages in the rotors during 15 the remainder of each revolution thereof, devices for directing combustion gases to the said blades during the said remainder of each revolution thereof, thereby then utilizing the said blades as turbine blades, and 20 inlet and outlet connections for the combustion gases.

4. In an apparatus of the class described, a casing, a plurality of wheels revolvably mounted therein, each wheel comprising a 25 primary disk, and a secondary disk spaced therefrom and secured thereto to provide a passage therethrough, a plurality of blades mounted in each wheel, means for admitting air into the casing and to the entrance to the 30 passages in the wheels during a part of each revolution thereof, for utilizing the said blades as compressor blades, means for closing the entrance to the said passages in the said wheels during the remainder of each 35 revolution thereof, means for directing combustion gases to the said blades during the said remainder of each revolution of the said wheels, for then utilizing the said blades as 40 turbine blades, and inlet and outlet connections for the combustion gases.

5. In an apparatus of the class described, a casing, a plurality of wheels revolvably mounted therein, each wheel comprising a primary disk, a secondary disk spaced there- 45 from and secured thereto, and webs between the said disks providing passages therethrough, a plurality of blades secured in each of the said wheels between the disks thereof; means for admitting air through 50 the casing and to the passages in each wheel during a part of each revolution thereof, for then utilizing the said blades as compressor blades, means for closing the entrance to the said passages through the said wheels during the remainder of each revolution 55 thereof, means for directing combustion gases to the said blades during the said remainder of each revolution thereof, to then utilize the said blades as turbine blades, and

inlet and outlet connections for the said combustion gases.

6. In an apparatus of the class described, a casing, a plurality of wheels revolvably mounted therein, each wheel comprising a primary disk, a secondary disk spaced therefrom and secured thereto, and webs providing passages extending therethrough, a plurality of blades mounted between the disks of each wheel, and extending therebeyond, means for admitting air through the casing and to the passages through the said wheels during a part of each revolution thereof, to then utilize the said blades as compressor blades, partition walls in the casing closing the entrance to the said passages in the wheels during the remainder of each revolution thereof, means for directing combustion gases to the said blades during the said remainder of each revolution of the said wheels, for then utilizing the said blades as turbine blades, and inlet and outlet connections for the said combustion gases.

7. In an apparatus of the class described, a casing, a plurality of spaced wheels revolvably mounted therein, each wheel comprising a primary disk, a secondary disk spaced therefrom and secured thereto, and webs between the said disks forming a plurality of passages between the same, the entrance to the said passages in each wheel being substantially axial, and the discharge from the said passages being substantially radial, there being passages in the casing between the discharge from one wheel and the entrance to the passages to the next succeeding wheel, a plurality of blades mounted between the disks of each wheel, and extending therefrom, means for admitting air into the casing and to the entrance to the said passages in the said wheels during a portion of each revolution thereof, to then utilize the said blades as compressor blades, partition walls in the casing for closing the entrance to the passages in the wheels during the remainder of each revolution thereof, and a series of director plates for directing combustion gases to the blades of each wheel during the said remainder of each revolution thereof, for then utilizing the said blades as turbine blades, there being a passage in the casing between each of the said wheels for the said combustion gases, and inlet and outlet connections for the said combustion gases.

In testimony whereof I have affixed my 115 signature.

LÉON DUFOUR,
